UNITED STATES PATENT OFFICE.

OSCAR HOCHBERG, OF NEW YORK, N. Y., ASSIGNOR TO AMERICAN CAR AND FOUNDRY COMPANY, OF NEW YORK, N. Y., A CORPORATION OF NEW JERSEY.

GENERAL-SERVICE RAILWAY CAR.

1,405,415.

Specification of Letters Patent. Patented Feb. 7, 1922.

Application filed November 3, 1919. Serial No. 335,366.

To all whom it may concern:

Be it known that I, OSCAR HOCHBERG, residing at New York city, New York County, New York, and being a citizen of the United States, have invented certain new and useful Improvements in General-Service Railway Cars, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

20 In said drawings:

Figure 1 is a side elevational view of that portion of the car above the trucks, showing in broken lines the position of the wheels of the truck;

25 Figure 2 is a similar view of a portion of the car extending between the trucks;

Figure 3 is an end elevational view;

Figure 4 is a plan of a portion of the car extending from the end and side walls to 30 beyond the middle of the car and beyond the center sills;

Figure 5 is a transverse sectional view of one side of the car, the section being taken on line 5—5 of Fig. 1, looking in the direction indicated by the arrow showing the doors in closed position and indicating in broken lines the dropped or dumping position of said doors;

Figure 6 is a similar view, the section being taken on line 6—6 of Fig. 2, looking in the direction indicated by the arrow;

Figure 7 is a longitudinal sectional view of an intermediate portion of the car, the section being taken on line 7—7 of Fig. 6, 45 looking in the direction indicated by the arrow, and showing the upper portion of the side wall broken away;

Figure 8 is a similar view of that portion of the car overlying the trucks, the section being taken on line 8—8 of Fig. 5, looking in the direction indicated by the arrow.

My invention relates to that class of railway cars primarily designed to carry coal

or similar lading and which are adapted for use in hauling long materials such as 55 lumber, steel rails, pipe and the like.

The object of my invention is to provide a car of great pay-load capacity and of minimum length and height, and low center of gravity.

A further object is to provide a car of the character mentioned in which the floor is substantially wholly made up of drop doors, so that such car, when used in coal carrying or like service, will be entirely 60 self-clearing.

A particular and further object is to so arrange the floor and dispose the drop doors thereof that a large part of the space between the trucks of the car may be utilized 65 for load-carrying purposes.

Other objects and advantages will appear in connection with the detailed description of the parts, of which, 1 indicates the wheels of the truck; 2 the center sill extending 70 preferably throughout the length of the car and which may be built up as shown in the drawings, comprising a pair of rolled members 3 spaced apart and united by means of the usual cover plate 4 which may extend 75 the full length of car if desired; that portion of the center sill extending between the trucks may be further provided with shedding caps 5 to expedite discharge of the lading at this point.

The center sills are supported above the trucks by means of the bolsters 6 comprising diaphragms 7, top cover plate 8, bottom cover plate 9, center plate 10, and side bearings 11, all as shown clearly in Figs. 5 80 and 8. Supported by said bolsters 6 are side walls 12, designed to carry the greater part of the load at points intermediate the bolsters and said walls are made up in the conventional manner, that is to say, in the 85 form of a girder comprising a web-plate 13 having preferably a load deflecting portion 14, top chord 15, side stakes 16, and lower chord 17. Spaced inwardly from the bolsters 6 to provide door openings, and supported by the side walls 12, are cross bearers 18 for transmitting load stresses in the center sills between the bolsters to the side walls. These cross-bearers 18 comprise dia-

90 phragms 19, top chords 20, and bottom 95 chords 21, and, with bolsters 6, extend in 100 105

wardly from the side wall of the car, or if desired, inwardly and upwardly, as shown.

Between the cross-bearers 18 and intermediate the trucks of the car, I provide secondary cross bearers or floor beams 22, which may be made up as shown in Figures 6 and 7, of web pieces 23, cover plates 24, and bottom pieces 25. These floor beams are arranged in series on each side of the center 10 sill as indicated in Figs. 4 and 7, and are spaced apart to provide door openings between them. The upper margins of the floor beams 22 slope downwardly and inwardly from the side wall to the center sills 15 and extend in planes below the planes of the upper margins of the bolsters 6 and main cross-bearers 18.

Positioned within the door-openings formed by the spaced floor-beams 22 and by 20 the floor-beams and adjacent cross-bearers 18, are drop doors 26 pivoted to the center sill at 27 and extending upwardly toward the side wall where their free edges close against abutments 28 of the side walls. Said 25 abutments together with projections or door framing members 29 on cross-bearers 18 and the projecting load deflecting edge 30 on the shedding cap 5 of the center sill, operate as seals to prevent the escape of granular 30 lading, through the joints at the door edges.

Supported at the side of the car and adjacent the free edges of the doors are door-operating shafts 31 arranged on each side of the car and adapted, as in the embodiment shown, to carry the load through the medium of latches 32 depending from the underside of the doors. These shafts, preferably in two sections, extend from end to end of car and are actuated by suitable operating devices 33 mounted on the ends 12^a of the car as best shown in Figs. 1 and 3. In a similar fashion said shafts between main cross-bearers 18 and the ends of the car operate doors 26^a received in the openings between said cross-bearers and bolsters 6 and between said bolsters and the car ends.

The doors 26^a are hinged at a higher level than are the doors intermediate the trucks in order to provide sufficient slope for said 50 doors when in the dropped or dumping position over the trucks. For this purpose these doors are hinged to a rail 34, of suitable section, extending from cross-bearer 18 to the car end; this rail is held in position between

55 bolster and cross-bearer diaphragms 7 and 19 to which it is secured, and to end wall of car by suitable connections 35. If greater stability is desired, the rail 34 may be further reinforced by brace plates 36 resting 60 upon the sills at points between bolster and end wall of car and between bolster and cross-bearer, substantially as shown in Figs. 1, 4, 5, and 8, and by a top shedding plate 5^a. From the foregoing it is clear that the 65 floor doors 26^a over the trucks are hinged at

a point preferably above the level of operating shaft 31, and the doors 26 between the trucks hinged below the level of said operating shaft. Although the doors 26 and 26^a may be pivoted at points respectively 70 below and above shaft 31, the front or free edges of said doors when closed rest in planes preferably above said shafts thereby permitting all of said doors to be supported at the car sides in a common plane though 75 pivoted in different vertical and horizontal planes. It will be further noted that the set of doors 26 between the trucks and the set of doors 26^a above the trucks lie respectively 80 in planes intersecting at a point approximating the free edges of all of said doors. By thus bringing the free edges of both sets 85 of doors to a common plane when in their closed position I am enabled to use an operating shaft common to the doors above and between the trucks without necessitating the use of different types of door operating mechanism for each set of doors. A further advantage is that since the doors are positioned substantially in the plane of the upper margins of the cross-members, the floor 90 of the car between the cross beams and on opposite sides of the center sill and over the trucks presents no obstruction to the loading of long materials. If some of the 95 long material desired to be carried is of no greater length than the distance between the cross beams, that portion of the lading may fill the space between said cross beams, and the lading of greater length rest upon the floor portions over the trucks and spanning the depressed intermediate floor pockets with their lading of lesser length, thus utilizing the entire cubic capacity of the car. The 100 sloping of the depressed flooring between the trucks towards the center sill and the hinging of the doors thereof in a plane below the free edges thereof provides maximum load capacity for the car and permits a large 105 radius of movement for the doors in their progress to open position for the rapid discharge of the lading through large unobstructed openings between the car side and the free edges of said doors.

What I claim is:

1. In a dumping car, side and end walls, a floor extending from wall to wall and composed substantially wholly of doors hinged longitudinally of the car at different levels, and a door operating shaft adjacent to and below the free edges of all of said doors.

2. In a dumping car, side and end walls, a floor extending between said walls and comprised largely of drop-doors hinged longitudinally of the car at different levels, and a door operating shaft adjacent to and below the free edges of all of said doors.

3. In a dumping car, a pair of side and end walls, a floor substantially wholly composed of drop-doors and extending from 130

- wall to wall at different levels, and a door operating shaft extending longitudinally of the floor and below the free edges of all of said doors.
- 5 14. In a dumping car, side and end walls, a floor extending between said walls and composed largely of drop doors hinged longitudinally of the car at different levels and arranged to dump outwardly, and a door operating shaft adjacent to and below the free edges of all of said doors.
- 10 15. In a dumping car, side and end walls, a floor extending between said walls and substantially wholly composed of drop doors hinged longitudinally of the car and at different levels and certain of which doors incline upwardly toward the side of the car, and an operating shaft arranged adjacent to and below the free edges of all of the doors.
- 15 20. 6. In a dumping car, side and end walls, a floor extending between said walls and comprised largely of drop doors hinged longitudinally of the car at different levels and arranged to dump outwardly, certain of which doors incline upwardly toward the car side, and an operating shaft arranged adjacent to and below the free edges of all of the doors.
- 25 7. In a dumping car, side and end walls, a floor extending between said walls and substantially wholly composed of drop doors hinged longitudinally of the car in different horizontal planes and certain of which doors incline upwardly toward the car side, and an operating shaft arranged adjacent to and below the free edges of all of the doors.
- 30 8. In a dumping car, side and end walls, a floor extending between said walls and comprised largely of drop doors hinged longitudinally of the car in different horizontal planes and arranged to dump outwardly, certain of which doors incline upwardly toward the car side, and an operating shaft adjacent to and below the free edges of all of the doors.
- 35 9. In a dumping car, side and end walls, a floor extending between said walls and composed substantially wholly of drop doors arranged with their free edges in a common horizontal plane and opposite pivoted edges at different levels, and door operating shafts adjacent to and below the free edges.
- 40 10. In a dumping car, side and end walls, a floor extending between said walls and composed substantially wholly of drop doors hinged longitudinally of the car and with their free edges arranged in a common horizontal plane and opposite pivoted edges at different levels, and door operating shafts adjacent to and below the free edges.
- 45 11. In a dumping car, side and end walls, a floor extending between said walls and comprising doors arranged with their free edges in a common horizontal plane and opposite pivoted edges at different levels, and
- 50 12. In a dumping car, side and end walls, a floor extending between said walls and composed substantially wholly of drop doors arranged longitudinally of the car and hinged at different levels, door operating shafts arranged adjacent to the free edges of said doors, said free edges being arranged in a common horizontal plane.
- 55 13. In a dumping car, side and end walls, a floor extending between said walls and composed substantially wholly of drop doors hinged longitudinally of the car and at different levels, door operating shafts arranged adjacent to the free edges of said doors, said free edges being arranged in a common horizontal plane.
- 60 14. In a dumping car, side and end walls, a floor extending between said walls and composed substantially wholly of drop doors hinged at different levels with their free edges arranged in a common horizontal plane, and door operating shafts adjacent to and below said free edges.
- 65 15. In a car of the class described, a plurality of outwardly dumping doors over the trucks, and a plurality of doors inclined when closed and hinged longitudinally of the car between the trucks and at a level below the free edges of some of said doors.
- 70 16. In a car of the class described, a plurality of outwardly dumping doors over the trucks and hinged at a level above the free edges thereof, and a plurality of inclined doors hinged longitudinally of the car between the trucks and at a level below the free edges of some of said doors.
- 75 17. In a car of the class described, a plurality of outwardly dumping doors over the trucks, and a plurality of outwardly dumping doors inclined when closed and hinged longitudinally of the car between the trucks and at a level below the free edges of said doors.
- 80 18. In a car of the class described, a plurality of outwardly dumping doors over the trucks arranged at a level above the free edges thereof and a plurality of inclined doors hinged longitudinally of the car between the trucks and at a level below the free edges of said doors.
- 85 19. In a car of the class described, a plurality of outwardly dumping doors over the trucks arranged at a level above the free edges thereof and a plurality of outwardly dumping inclined doors hinged longitudinally of the car between the trucks and at a level below the free edges of said doors.
- 90 20. In a dumping car, side and end walls, floor framing members over the trucks, downwardly and inwardly inclined floor framing members between the trucks having their upper margins at a lower level than those of the first mentioned floor framing.

- members, and outwardly dumping doors between said wall and floor framing members.
21. In a dumping car, side and end walls, 5 floor framing members having their upper margins high over the trucks and relatively low between the trucks, and outwardly dumping inclined doors arranged between said wall and floor framing members.
22. In a car of the class described, floor framing members over the trucks having their upper margins arranged at a high level, relatively low floor framing members between the trucks having their upper margins inclined downwardly and inwardly 10 from the sides of the car, and outwardly dumping doors positioned between said floor framing members and substantially in the planes of the upper margins thereof.
23. In a car of the class described, floor framing members over the trucks having their upper margins arranged at a high level and inclined downwardly toward the car side, relatively low floor framing members 15 between the trucks and outwardly dumping doors positioned between said floor framing members and substantially in the planes of the upper margins thereof.
24. In a car of the class described, floor framing members over the trucks having their upper margins inclined downwardly toward the car sides, relatively low floor framing members between the trucks arranged with their upper margins inclined 20 downwardly and inwardly from the sides of the car, and outwardly dumping doors positioned between said floor framing members and substantially in the planes of the upper margins thereof.
25. In a car of the class described, a plurality of outwardly dumping doors over the trucks arranged at a high level, and a plurality of relatively low outwardly dumping inclined doors between the trucks, said 25 doors being hinged in different vertical planes and inclined when in closed position.
26. In a car of the class described, a plurality of outwardly dumping doors over 30 the trucks arranged at a high level, and a plurality of relatively low outwardly dumping doors between the trucks, the planes of said doors intersecting at the free edges thereof.
27. In a car of the class described, a plurality of outwardly dumping doors over the trucks, and a plurality of relatively low outwardly dumping doors between the trucks, the planes of 35 said doors intersecting at the free edges thereof.
28. In a car of the class described, a plurality of outwardly dumping doors over the trucks arranged at a high level, and a plurality of relatively low outwardly dumping 40 doors between the trucks, the planes of said doors intersecting at the free edges thereof.
29. In a car of the class described, a plurality of outwardly dumping doors over the trucks arranged at a high level, and a plurality of relatively low outwardly dumping inclined doors between the trucks, the planes of 45 said doors intersecting at the free edges thereof.
30. In a car of the class described, a plurality of outwardly dumping doors over the trucks arranged at a high level, and a plurality of relatively low outwardly dumping doors between the trucks, all of said doors being inclined when in closed position.
31. In a car of the class described, a plurality of outwardly dumping inclined doors over the trucks arranged at a high level, and a plurality of relatively low outwardly dumping inclined doors between the trucks, 50 the planes of said doors intersecting at the free edges thereof.
32. In a car of the class described, a plurality of outwardly dumping inclined doors over the trucks arranged at a high level, and a plurality of outwardly dumping inclined doors hinged at a lower level, the free edges of all of said doors being supported in a relatively common horizontal plane.
33. In a car of the class described, a set of 55 outwardly dumping doors over the trucks arranged at a high level, and a set of outwardly dumping inclined doors hinged at a lower level, the free edges of all of said doors being supported in a common horizontal plane.
34. In a dump car, doors comprising substantially the entire floor of the car, a plurality of downwardly and outwardly inclined doors over the trucks arranged at a high level, a plurality of relatively low outwardly and upwardly inclined doors between the trucks, all of said doors being hinged longitudinally of the car with their free edges supported in a common horizontal 60 plane.
35. In a dumping car, a center sill, doors hinged to the center sill in different horizontal planes and having their free edges abutting the car side, the free edges of said 65 doors being supported in a common horizontal plane.
36. In a dumping car, a center sill, doors hinged to the center sill above the lower edge thereof and in different horizontal 70 planes and having their free edges abutting the car side in a common horizontal plane.
37. In a dumping car, a center sill, doors hinged to the center sill at different levels and abutting with their free edges against 75 the car side, all of said free edges being supported in a common horizontal plane.
38. In a dumping car, side and end walls, a floor extending between said walls and composed substantially wholly of doors, the 80

doors over the trucks being arranged at a high level with their free edges abutting the car side in a lower plane, and a plurality of relatively low doors between the trucks with their free edges abutting the car side in a higher plane.

39. In a car of the class described, a plurality of outwardly dumping doors over the trucks, a plurality of relatively low outwardly dumping doors between the trucks and inclined when closed, a door operating shaft adjacent to the free edges of said doors, and connections between said shaft and doors.

15 40. In a car of the class described, a set of outwardly dumping doors over the trucks, a set of relatively low doors between the trucks and inclined when closed, an operating shaft, and connections between said shaft and said doors.

20 41. In a car of the class described, floor

framing members over the trucks having their upper margins arranged at a high level, relatively low framing members between the trucks having their upper margins inclined downwardly and inwardly from the sides of the car, and outwardly dumping doors positioned between said floor framing members.

25 42. In a car of the class described, a set of outwardly dumping doors over the trucks arranged at a high level, and a set of relatively low outwardly dumping doors between the trucks, the planes of both sets of doors intersecting at the free edges thereof.

30 35 In witness whereof I have hereunto set my hand in the presence of two witnesses.

OSCAR HOCHBERG.
